UNITED STATES PATENT OFFICE.

PHILIP SHEINER, OF BROOKLYN, NEW YORK, ASSIGNOR TO METROPOLITAN LAMP CO.
INC., OF NEW YORK, N. Y., A CORPORATION OF NEW YORK.

DESIGN FOR A BASE FOR A LAMP.

Application filed May 12, 1926. Serial No. 17,663. Term of patent 7 years.

To all whom it may concern:

Be it known that PHILIP SHEINER, a citizen of the United States, residing at 1947 73rd Street, in the borough of Brooklyn, city of New York, New York, have invented a new, original, and ornamental Design for a Base for a Lamp, of which the following is a specification, reference being had to the accompanying drawing, forming a part thereof.

2 is a front elevation view of said base. I have shown only a portion of the ornamentation of said base for said lamp in Figure 1, the remainder within the marginal line involving a mere repetition of that part more fully shown.

I claim:

The ornamental design for a base for a lamp as shown.

In testimony whereof, I have hereunto affixed my hand this 10th day of May, 1926.

PHILIP SHEINER.
